(57) CLAIM

The ornamental design for an upper body outer garment with one front pocket, as shown and described.

DESCRIPTION

FIG. 1 is a perspective view of an upper body outer garment with one front pocket showing the design;

FIG. 2 is a front elevational view of the upper body outer garment with one front pocket of FIG. 1;

FIG. 3 is a rear elevational view of the upper body outer garment with one front pocket of FIG. 1;

FIG. 4 is a top plan view of the upper body outer garment with one front pocket of FIG. 1;

FIG. 5 is a bottom plan view of the upper body outer garment with one front pocket of FIG. 1;

FIG. 6 is a right elevational view of the upper body outer garment with one front pocket of FIG. 1; and

FIG. 7 is a left elevational view of the upper body outer garment with one front pocket of FIG. 1;

FIG. 8 is a front elevational view of the upper body outer garment with one front pocket of FIG. 1, as worn by a person in the standing position with one arm extended;

FIG. 9 is a perspective view of another upper body outer garment with one front pocket showing the design;

FIG. 10 is a front elevational view of the upper body garment with one front pocket of FIG. 9;

FIG. 11 is a rear elevational view of the upper body outer garment with one front pocket of FIG. 9;

FIG. 12 is a top plan view of the upper body outer garment with one front pocket of FIG. 9;

FIG. 13 is a bottom plan view of the upper body outer garment with one front pocket of FIG. 9;

FIG. 14 is a right elevational view of the upper body outer garment with one front pocket of FIG. 9;

FIG. 15 is a left elevational view of the upper body outer garment with one front pocket of FIG. 9; and,

FIG. 16 is a front elevational view of the upper body outer garment with one front pocket of FIG. 9, as worn by a person in the standing position with an arm extended.

The dash-dash broken lines in the drawings depict portions of the upper body outer garment with one front pocket that form no part of the claimed design. The long dash-dot broken lines in the drawings define the boundaries of the claim and form no part thereof. The broken lines in FIGS. 8 and 16 contain a human figure that does not form part of the claimed design.

1 Claim, 12 Drawing Sheets
